Primary Examiner — Lauren D McVey(74) *Attorney, Agent, or Firm* — Nitin Kaushik(57) **CLAIM**

The ornamental design for a label printer, as shown and described.

DESCRIPTION

FIG. 1 is a front perspective view of a label printer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 2.

The evenly spaced broken lines in the drawings depict portions of the label printer which form no part of the claimed design.

The dash-dot broken lines depict the bounds of the enlarged views and form no part of the claimed design.

1 Claim, 10 Drawing Sheets(56)
